UNITED STATES PATENT OFFICE.

CONRAD C. JACOBSON, OF GLEN RIDGE, NEW JERSEY, ASSIGNOR TO THE ARTESIAN WELL ENGINEERING CO., INC., OF NEWARK, NEW JERSEY, A CORPORATION OF NEW JERSEY.

AUTOMATIC CONTROL FOR AIR LIFTS.

Application filed October 6, 1923. Serial No. 667,049.

This invention relates to an automatic control for air lifts such as are used in the art of pumping and more specifically in the raising of water or other liquid from a well or other container by means of compressed air.

An extensively used arrangement in hydraulics consists in locating, in a well, an upright eduction-pipe with its lower end submerged below the water-level; there being 10 also an auxiliary air-pipe providing an air-nozzle directed into the lower end of the eduction-pipe; whereby the air delivered by said nozzle will mix with, and thus aerate, the column of water in the eduction-pipe 15 and cause the aerated-column to rise (by reason of its reduced specific gravity) above the water level in the well and escape from the delivery-end of the eduction-pipe. To obtain maximum efficiency, it is essential 20 that the amount of air let into the water be neither too great nor too little and the amount required for maximum efficiency is determined by the head of water above the air-inlet, as well as the total lift above the 25 pumping level of well. Stated differently, the pressure and rate-of-flow of the air, required for efficient operation, varies in a complex manner with the submergence of the air-nozzle; the higher the head of the 30 water, the greater the air-pressure, and conversely.

These so-called air wells are usually operated in groups, that is, several wells are connected to a central source of air-pressure 35 and, inasmuch as the seepage of water into each of the several wells of a group varies, (and through other causes) it often happens that the head of water in one well will be materially lowered, or even be level with the 40 air-inlet, before the other wells of the same group are similarly affected. With one of the wells in this condition, the air in the line naturally follows, under the pressure of its source, the course of least resistance, 45 with the result that the well requiring the least air will receive the most, and the one requiring the most will be "starved":—to the end that none of the wells of the group is likely to be operated at maximum efficiency. This condition not only greatly reduces the total quantities of water pumped, 50 but it also causes excessive waste of com-

pressed air which, being expensive, in turn renders the operation of the group of wells unduly costly.

In addition to the variance in the water supply in the different wells of the group (caused by the differential between the rates of pumping and the rates of seepage) all of the wells are subject to certain seasonal, 60 daily, and even hourly fluctuations from weather and geological conditions; and it has heretofore been impossible to regulate the flow and distribution of the air so as to compensate for each individual fluctuation 65 in the manner required for maintaining each of the wells in operation at a constant maximum efficiency.

It is an object of this invention to provide automatic means adapted to constantly regulate the flow of air into each well, (whether there be one or more in operation) so that each well will receive precisely the proper amount of air and at the correct pressure required according to its then-existing condition.

A further object of the invention is to provide an automatic air regulator for air-wells, which is controlled entirely by the head of water above a predetermined point.

These objects have been attained by locating, between the air-supply and the air delivery nozzle, an air-regulating device which is controlled by the pressure of the head of water in the well above a predetermined point to automatically regulate the flow of air so that each well is supplied with air in proportion to the head of water therein. Thus when the water-level in any well is lowered from a predetermined point the less 90 will be the amount of air supplied thereto, and conversely.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, 100 drawings depicting a preferred typical construction have been annexed as a part of this disclosure and, in such drawings, like characters of reference denote corresponding

parts throughout all the views, of which:—

Fig. 1 is a diagrammatic representation of a group of air-wells equipped with the apparatus necessary for operating them in a manner well understood, with which is combined one form of automatically controlled air regulating device embodying the present invention. Fig. 2 is an axial section of the air regulator shown in Fig. 1.

10 Referring to the drawings, 1 denotes a reservoir or container for the fluid to be pumped which, in this instance, is the water contained in a well formed by drilling a hole 2 downwardly into the ground 3. The 15 level of the water is indicated by 4; the elevation of which will, of course, be variable depending upon various circumstances such as the rate of pumping, the rate of seepage, etc. The water is drawn upwardly from 20 the well through a so-called eduction-tube 5 which is open at its lower end 6 located at an appropriate depth in the well or reservoir. The upper end 7 of the eduction-tube terminates as far above the ground as 25 may be desired and delivers its flow into a suitable receiver 8 from which the water is carried either to a central reservoir or to the point of consumption. A shield 10 may be arranged at the upper end of the eduction-tube to divert downwardly the water and prevent undue splashing thereof.

The air for operating the well is delivered through an orifice 11 into the lower end of the eduction-tube; such air being conveyed 30 to that point by means of a suitable air-pipe 12 which, in turn, receives the air from a main line 13 connected with the air-tank 14 of a compressor 15. The air flowing from the pipe 13 to the pipe 12 passes 35 through a flow-regulator A which has, in turn, its action determined by a controller B as will be presently described. Piping indicated by 16 and 17 carry the air to the regulator A which delivers it into 40 an auxiliary tank 18 from which it is conducted by a pipe 19 to the aforesaid air-pipe 12. A by-pass 20 may be used to disconnect the regulator when it is desired to 45 make certain temporary observations. This 50 may be done by closing the valves 21 and 22 and opening the valve 23; the converse being the normal seating of said valves.

In order that the action of the regulator A may be dependent upon the extent of submergence of the eduction-pipe 5, with respect to the then-existing level 4 of the water in the well, the instrumentality will embody a means in the nature of a level-gauge for ascertaining the then-existing level of the 55 water; such means being here shown in the nature of an indicator-tube 24, the lower end of which is located at a predetermined point 25 with respect to the lower end 6 of the eduction-tube; either above, or level 60 with, or even below said lower end, depend-

ing upon the particular construction of the controller B, as will presently appear. This indicator 24 leads to the controller B and derives from the latter a slight flow of air; just sufficient to keep the submerged portion 70 of the tube 24 free at all times from any fluid in its bore and thereby enable it accurately and positively to indicate, by its air pressure, the head of the water in the well above the lower end 25 of said tube. 75

The nature and the principles of the construction of the combined regulator and controller can thus be understood by referring to Fig. 2. The regulator B embodies a passage, the inlet of which is denoted by 26 and 80 the outlet by 27. This passage is provided by suitable formation of a casing 28 which makes provision for an intervening choke-valve for regulating the flow of the air. This valve may, of course, be constructed in 85 various ways consistent with the capacity for automatic regulation and a representative construction is that shown on the drawings and a valve-cage 29 is transversely seated in a tubular portion 30 of the casing 90 having a closed end. The cage preferably provides two circular valve seats 31 and 32 and appropriate openings 33 and 34 leading to or from said seats, as shown, to provide for the passage of the air except in 95 so far as it is restricted or choked by the valve proper. This comprises a shiftable valve stem 35 the position of which is controlled by the controller B. A sleeve-like valve 36 is carried on said controller and is 100 normally retained in a definite relation therewith by an expansible spring 37 bearing at one end against a head 38 of the stem 35 and arranged to urge the sleeve-like valve 36 against a shoulder 39 provided by the 105 other end of the stem 35. These parts normally shift as a unit thereby bringing the seats 40 and 41 closer to or further away from the seats 31 and 32 to regulate the 110 flow of air. The cage, or other parts of the casing, provide suitable slideways for the aforesaid shifting as a unit of the valve mechanism.

The means for determining the position of the valve mechanism comprises a diaphragm 115 42, or other element which is actuated by the differential in pressure between the air in the outlet 27 and the air in the gauge tube 24. This diaphragm separates the chamber 43 (containing the air under the pressure used for pumping) from a chamber 44 containing the air under the pressure of the head of the water in the well above the point 25 of the gauge tube. The chamber 44 is formed by a suitably shaped casing 45 which forms a part of the control device B. It will be perceived that, as in the case shown, when the location of the point 25 is not so far below the level of the water 120 in the well as the lower end of the eduction- 125 130

tube 6, the air pressure in the chamber 44 will be less than that on the other side of the diaphragm in the chamber 43 and it is, therefore, desirable to provide a constant pressure on the low pressure side of the diaphragm which will be auxiliary to the air pressure and to provide for a convenient adjustment to provide any air pressure desired. To that end, the controller B provides an expansile spring 46 which exerts a constant and substantially uniform pressure against the diaphragm in opposition to the pressure presented by the air in the chamber 43. This spring, or its equivalent, 15 may be arranged in any appropriate manner, as for example, by being located in a closed tube 47 provided by the casing 45 of the controller B. One end of the spring bears against an abutment 48 which is translatable 20 within the bore of the tube 47; being restrained from rotation by a feather 49. The abutment 48 is screw-threaded to a bolt 50 which is rotatably journaled through a cap 51 which is screw-threaded into the outermost end of the tube 47 and closes the latter. The bolt 50 has a valve-like shoulder 52 which prevents any escape of air through its journal and, by applying a wrench to the extremity 53, the bolt may be turned 25 and the abutment 48 thereby shifted to adjust the tension of the spring 46. A cap 54 may normally cover the extremity of the bolt and form an additional security against the escape of air.

30 The other end of the spring bears against a seat 55 of a collar 56 which is threaded to the stem of a member 57 passing through a central orifice of a diaphragm 42. This diaphragm bears against an annular shoulder 58 provided by the member 57 and a soft metal washer or gasket 59 intervenes between the collar 56 and the adjacent diaphragm so as to form a rigid connection between these parts and prevent escape of 35 air. The member 57 is enlarged on the high pressure side of the diaphragm, as indicated by 60, and this enlargement is so proportioned and formed that it may (when the valve 36 is wide open) abut against a shoulder 61 provided by the casing and limit further movement of the diaphragm in case, for any reason, the pressure should become excessive in the chamber 44 on the low pressure side of the diaphragm. The enlargement 60 is appropriately connected with the stem 35 of the valve, as by means of a pin 62 passing through an ear 63 provided by the stem 35. This ear provides a shoulder 39 for maintaining the valve sleeve 36 in its normal position on the stem.

40 The foregoing description has alluded to but one diaphragm, to wit that marked 42, and it may be here stated that a highly efficient regulation may, as has been demon-

strated by practice, be obtained through the use of a single diaphragm. However, a double or compound diaphragm is likewise contemplated by this invention; such, for example as two diaphragms 42 and 42^a:— 45 which case an advantageous differential effect may be had by making these work as a unit and by having the one (42^a) larger in area than the other. A ratio of about 1.15 is recommended in that case.

50 These two differently sized diaphragms are spaced apart and clamped between the casings 45 and 28 by means of an annular ring 64 which is beveled, as indicated by 65, to give the larger diaphragm a free range 55 of movement consistent with its larger size. One or more escape vents 66 are preferably provided in the ring 64 so that the compound diaphragm may not become air-bound as to the space intervening between 60 them. So that the force yielded by the flexation of the larger diaphragm may be fully transmitted to the smaller diaphragm, and conversely, an intermediate spacer-ring 67 is provided and this ring is held against 65 undue lateral displacement by a collar 68 which is tapered in thickness, as shown, so as not to interfere with the flexation of the diaphragm.

70 When the pressure on the depth gauge side of the diaphragm drops, the diaphragm will bend towards that side but to prevent it from being subjected to any undue pressure in that direction or from bulging too much, the casing 45 provides an annular 75 abutment 69 in the region of the spacer-ring 67. When flexing in that direction, the diaphragm gradually closes the valve 36 and ultimately said valve is brought firmly 80 against its seats. However, the pressure 85 may continue still further against the diaphragm and, in that event, the said seats would have to carry undue strains were it not for the fact that the movement of the valve 36 is then arrested although the stem 90 35 may continue to move slightly, the spring 37 allowing for this action.

95 It has been previously pointed out that a certain amount of air is permitted to escape through the pipe 24 to keep it clear of water. This pipe is connected at the point 100 70 to the chamber 44 and a slight amount of air is able to pass from the chamber 43 through the port 73, into the bore 72 and finally pass the slight clearance space 71 105 existing between a wiping valve 74 and the member 57. This needle 74 may be mounted in the end of bolt 50. The object of this arrangement is to take advantage of the vibrations of the diaphragm in keeping the clearance space 71 sufficiently open and free 110 from dirt to permit a little air always to escape. It is, of course, immaterial to the invention, where the escape vent is located but it is desirable to so arrange it that it 115

120

125

130

will be automatically self-cleaning. The purpose of the small opening 75 (which is normally closed by a plug) is to enable a pressure gauge to be temporarily inserted 5 at the time the apparatus is initially set up and used in turning the correct initial adjustment of the spring 46.

It will thus be perceived that this invention is well adapted to accomplish the purposes set forth. The valve is so regulated 10 by the pressures at the opposite sides of the diaphragm that, should the water level in the well fall as low as the end of the control pipe, the ports will be entirely closed and 15 the air will cease to flow through the pipe 5 until the water level rises and causes pressure to build up in the control pipe and compartment 44 and again open the valve, whereby the well is prevented from blowing 20 air when the head of water is reduced below a predetermined minimum; and intermediate effects will be obtained as has already been explained.

Without further analysis, the foregoing 25 will so fully reveal the gist of this invention that others can, by applying current knowledge, readily adapt it for various utilizations by retaining one or more of the features that, from the standpoint of the prior 30 art, fairly constitute essential characteristics of either the generic or specific aspects of this invention and, therefore, such adaptations should be, and are intended to be, comprehended within the meaning and range of 35 equivalency of the following claims.

Having thus revealed this invention, I 40 claim as new and desire to secure the following combinations and elements, or equivalents thereof, by Letters Patent of the United States:—

1. An air-regulator for air wells comprising a casing providing a chamber having an inlet connected with a pressure line and an outlet connected with said well; a valve 45 mechanism for controlling the flow of air into said chamber; a second chamber adjacent said first-mentioned chamber; a diaphragm separating said chambers; and means for maintaining air pressure in said 50 second chamber in proportion to the head of water in the well; said valve being connected with said flexible diaphragm and adapted to be opened and closed thereby to regulate the flow of air into said first-mentioned chamber in proportion to the differential in the pressures in the two chambers.

2. An air-regulator combining a casing 60 providing an air chamber having inlet and outlet openings; a relatively high pressure air line connected with said inlet opening; a valve for regulating the flow of air into said chamber; a second chamber adjacent said first-mentioned chamber; a relatively 65 low pressure line connected to said second chamber; a diaphragm separating said two

chambers; a spring located within said second chamber and acting on said diaphragm in opposition to the pressure in said first-mentioned chamber, said valve being connected with said diaphragm and adapted to 70 be opened and closed thereby in its flexing movements due to the differential in the air pressures in said chambers.

3. In combination with an air-well; an air-pressure line; an eduction-pipe; an air-pipe connecting said air-pressure line with the lower end of said eduction-pipe for aerating the water therein; an automatic air regulator connected with said air-pipe for varying the flow of air therethrough in proportion to the head of water in the well; and an automatic control for said air-regulator comprising a gauge-tube connected at one end to said regulator and having its other end open and projecting downwardly 80 into the water in the well, the air in said tube being maintained under pressure by the head of water above the lower end thereof, said regulator being so constructed and arranged that the air pressure in the tube 85 automatically controls the action of said regulator.

4. A fluid regulator combining a casing providing a high pressure chamber and an opposed low pressure chamber; a diaphragm separating said chambers; a relatively high pressure pipe connected with said high pressure chamber; a relatively low pressure pipe connected with said low pressure chamber; a spring located within said low pressure chamber and acting upon said diaphragm in opposition to the pressure in said high pressure chamber, a valve for regulating the flow of fluid into said high pressure chamber, said valve being connected with said diaphragm and adapted to be opened and closed thereby in its flexing movements due to the differential in pressures in said chambers; means for limiting the movements of 95 said diaphragm; and means for regulating the pressure of said spring.

5. In combination with an air-well, an eduction pipe; an air pressure line having one end connected with the lower end of said eduction pipe to aerate the water therein; an air-regulator connected with said air-pressure line and adapted to regulate the flow of air therethrough; said regulator comprising a casing providing a pressure chamber having inlet and outlet openings connected with said air pressure line; a second pressure chamber adjacent said first-mentioned chamber; a gauge tube having one end connected with said second chamber and having its other end extending substantially below the surface of the water in the well, thus producing air pressure in said second chamber; a diaphragm separating said two chambers; a valve mechanism, connected to 115 said diaphragm and actuated by the move- 120

125 130

ment thereof caused by the differential in pressures in the two chambers, for regulating the flow of air into the well.

6. A fluid regulator combining a casing providing two opposed pressure chambers; a relatively high pressure pipe connected with one of said chambers; a relatively low pressure pipe connected with the other of said chambers; two spaced diaphragms of unequal diameters, separating said chambers, the larger diaphragm being adjacent said low pressure chamber; and a valve for regulating the flow of fluid into said high pressure chamber said valve being connected with one of said diaphragms and adapted to be opened and closed by the flexing movements thereof due to fluctuations in pressure in said low pressure chamber.

7. A fluid regulator combining a casing providing two opposed pressure chambers each provided with a fluid inlet, a pressure line connected with each inlet, two diaphragms separating said chambers; an annular ring, provided with a vent, between said diaphragms for holding them in spaced relation, said vent preventing the building up of pressure between said diaphragms; a valve for controlling the flow of fluid into one of said chambers, said valve being connected with one of said diaphragms and adapted to be opened and closed by the flexing movements thereof due to the differential in pressures in said chambers.

8. In combination with an air-well having an eduction pipe, means for admitting air into said eduction pipe in proportion to the head of water above a predetermined point, said means comprising an air pressure line provided with an adjustable valve, and an automatically actuating regulator for opening and closing said valve; said regulator including a gauge tube having an open end extending into the well and below the water level thereof; and means for admitting air into said tube to keep it free from water.

9. The combination set forth in claim 5,

characterized by this, that a vent is provided between the two chambers to permit a constant seepage of air from the first chamber into the second chamber and out through the gauge tube to prevent water from entering the tube.

10. An air-regulator combining a casing providing relatively high and low pressure chambers, a high pressure air line connected with said high pressure chamber; a low-pressure air-line connected with said low pressure chamber; a movable element separating said chambers and adapted to be moved by the differential in the pressures upon its opposite sides; a spring located within said low-pressure chamber and acting on said movable element in opposition to the pressure in said high-pressure chamber; a valve connected with said movable element and arranged to control the flow of air into said high pressure chamber; means for adjusting said spring to vary its pressure against said movable element to effect a predetermined setting of the valve, said valve and movable member being so constructed and arranged that fluctuations in pressure in the low pressure chamber effect adjustments of said valve.

11. The combination set forth in claim 5, characterized by this, that a vent is provided between the two chambers to permit a constant seepage of air from the first chamber into the second chamber and out through the gauge tube to prevent water from entering the tube and that a needle, relatively movable with respect to said vent, is provided for keeping said vent free from dirt.

12. The combination set forth in claim 7 characterized by this that a loose spacer ring is located between the two diaphragms, and means is provided for preventing lateral displacement of said spacer ring.

In witness whereof, I hereunto subscribe my name.

CONRAD C. JACOBSON.
